(57) **CLAIM**

The ornamental design for a screw fastener, as shown and described.

DESCRIPTION

FIG. 1 is an elevated perspective view of the screw fastener of our claimed design;

FIG. 2 is a front view of the screw fastener of FIG. 1;

FIG. 3 is a back view of the screw fastener of FIG. 1;

FIG. 4 is a left side view of the screw fastener of FIG. 1;

FIG. 5 is a right side view of the screw fastener of FIG. 1;

FIG. 6 is a top view of the screw fastener of FIG. 1; and,

FIG. 7 is a bottom view of the screw fastener of FIG. 1.
